CONDUCTING RUBBER HEATING ELEMENT

Raymond A. York, Pitman, and Charles H. Taylor,
Haddonfield, N. J., assignors to Radio Corpora-
tion of America, a corporation of Delaware

Application August 29, 1947, Serial No. 771,240

4 Claims. (Cl. 219—46)

1

This invention relates to a novel type of heater element utilizing a heat radiator comprising conducting rubber and to an improved blanket structure utilizing the novel heater element.

Various types of electrically heated blankets have been proposed heretofore. The type most generally used includes a heating element, consisting of a spiral wound wire of copper or cadmium bronze. The spiral is coated with insulation and is either woven into the blanket fabric, threaded through the fabric or stitched to the inner side of the fabric. While these blankets have been successful commercial articles, they have several disadvantages. It is difficult to assemble the heater wire into the blanket; the thin strands of wire eventually wear out and break if the blanket is folded many times and the safety features to protect against breakage have not received unqualified approval from the underwriters. Since the radiating surface is relatively small, heat is more or less localized and may become excessive should the control circuit not be working properly and the blanket be folded with the current left turned on and running at full strength. When a strand of wire breaks, arcing may occur and the spark may set the blanket on fire. While this is not likely to happen when the blanket is fairly new, the danger becomes increasingly great with the age of the article.

In the present invention, none of the above mentioned disadvantages are present since the heating element is composed of a gridwork of strips of conducting rubber having a broad surface area and carrying a very low current. The rubber being tough and flexible can be folded or bent into any shape innumerable times without danger of tearing or breaking and even if a deliberate attempt is made to cut the blanket with the current on, the ruptured ends of the rubber are blunt and have very low electrical conductivity; hence, no arcing occurs which might cause a dangerous spark. It can be proved, experimentally, that arcs drawn from the ruptured rubber are of such low intensity that even cotton soaked in alcohol cannot be ignited.

Many other advantages will be readily seen in using a heating element constructed according to the present invention and some of these additional advantages will be noted hereinafter in the more complete description of the invention which follows:

One object of the present invention is to provide an improved heating element.

Another object of the invention is to provide

an improved heating element which is very resistant to breaking.

Another object of the invention is to provide an improved heating element which does not add to the bulk of a finished article when used to supply heat to a blanket.

Another object of the invention is to provide an improved heating element which is entirely flexible.

Another object of the invention is to provide an improved heating element having a large radiation surface and, hence, giving necessary amount of heat without use of high temperatures.

Another object of the invention is to provide a heating element which will radiate adequate heat but require a very low current to flow in each of its sections.

Another object of the invention is to provide an improved heating element which will lend itself to being formed into any desired shape.

Another object of the invention is to provide a heating element which can readily be assembled within a blanket.

Another object of the invention is to provide a novel heating element having an improved temperature sensitive element integrally attached thereto.

Another object of the invention is to provide an improved electrically heated blanket.

Another object of the invention is to provide a blanket of the electrically heated type having an improved safety construction.

Still another object of the invention is to provide an improved blanket of the electrically heated type having a structure which is not affected by laundering processes.

These and other objects will be more readily apparent and the invention will be better understood from the specification, including the following drawings, of which

Fig. 1 is a plan view of an improved heater element.

Fig. 2 is a perspective view of an improved heater element made according to the present invention and inserted within a blanket,

Fig. 3 is a cross section view taken laterally across the article illustrated in Fig. 2, along the line III—III,

Fig. 4 is a partly cut away view in perspective of one type of heater strip used in the invention.

Fig. 5 is a partially cut away perspective view of the heater strip as shown in Fig. 4 but with a current supply wire running therethrough.

Fig. 6 is a perspective view, partially cut away, of a strip of non-conducting rubber carrying a wire leading to a temperature sensitive device as used in the present invention, and

Fig. 7 is a partially cut away perspective view of a modification of the heater strip of Fig. 4.

Referring to Fig. 1, there is shown a grid 2 of thin rubber strips vulcanized together at their crossover points, which grid includes the heating element as used in the present invention. This grid has transverse strips 4, which may have a structure more particularly shown in Fig. 4, although not limited thereto. As shown in Fig. 4, these strips 4 are made up of three plies vulcanized together. An inner ply 6 is made of conducting rubber, which may be of a conventional type, having a large percentage of acetylene black uniformly dispersed throughout a rubber matrix. On either face of the inner conducting ply 6 and extending around its edges so as to completely encase it are vulcanized plies 8 and 10 of non-conducting rubber. One of these outer plies 10 may have fibrous material incorporated therewith in order to prevent undue stretching when the article is in use. Connecting these transverse strips 4 is a central strip 12 and two edging strips 14 of three-ply structure, similar to that of the transverse strips 4 but having a metal conductor 16 embedded in the central ply 18. This metal conductor may consist of a fiber core 20, upon which is wound a two-strand copper wire 22. Embedding the bare copper wire in the ply of conducting rubber provides a very good electrical contact, and protects wire from sharp bending. Transverse end strip 24 is of similar construction to central strip 12 and edging strips 14 in that the current conductor 16 is embedded in a central ply of conducting rubber. However, the inner ply is off-centered similar to the modification shown in Fig. 7 so that other wires 30 may be embedded in a ply of non-conducting rubber. The end strip 24 carries wires 22 and 30 to a single lead strip 26 of non-conducting rubber.

Other longitudinal strips 28, composed of non-conducting rubber, have embedded therein the wires 30 connecting temperature sensitive elements 32 in series circuit. These temperature sensitive elements 32 are preferably embedded in non-conducting corner pieces 34 vulcanized to the rubber grid. A transverse strip 29 similar in construction to the strip 44 shown in Fig. 7 carries the circuit wire 30 to complete the circuit through the temperature sensitive elements. The temperature sensitive elements 32 are connected to a control circuit (not shown) through the conductors 30 embedded in the lead strip 26 and running to the non-conducting strips 28 through the transverse end strip 24, to which the lead strip 26 is integrally connected.

The entire rubber grid is preferably attached to a sheet of loosely woven mesh material 36, such as cotton net or cheesecloth. The rubber strips are preferably loosely sewn or tied to the material with the stitches passing around rather than through the rubber strips. This prevents curling or other permanent distortion of the heater unit when in use.

The heating unit is then inserted within the double faces 38 of the blanket envelope, as more particularly shown in Fig. 2, and the heater unit support material 36 is stitched to the edges 40, only, of the blanket, the stitches being concealed by the edging strips 42.

One or more of the blanket edges may be provided with a "zipper" or snap fasteners so that

the heating unit may be removed or inspected with facility.

The above described improved construction results in several advantages which will be readily apparent. The rubber gridwork is very light in weight since the strips may be but $\frac{1}{2}$ inch in width and 0.045 inch in maximum thickness. The strips are moreover preferably tapered at the edges to still less thickness, making a unit adding no noticeable thickness or bulk to the blanket.

The type of construction described also provides a heater unit composed of a large number of parallel heating circuits resulting in the power in any one circuit being so low that if a break should occur due to injury to the blanket the current will be insufficient to cause arcing with its accompanying fire hazard.

The use of the center and side current leads provides means of applying different amounts of power to the two halves of the heater unit grid, thus allowing the use of a single or dual control circuit. A dual control circuit permits obtaining a temperature differential between the two halves of the heater unit.

Arching hazard due to strip breakage may be still further reduced, if desired, by providing extra conducting rubber ribbons 44 parallel to the side conductors 14 and taking the place of ribbons 28 shown in Figs. 1 and 2. This establishes equal potential lines at $\frac{1}{2}$ or $\frac{1}{3}$ line voltage. These extra conducting ribbons 44 may be of the modified form shown in Fig. 7 in order to, at the same time, contain the circuit wires 30 connecting the temperature sensitive elements 32. As shown in the figure, a conductive ply 46 may be encased between two non-conducting plies 48 and 50 with the central ply 46 being positioned off-center so as to allow room to embed the circuit wire 30 along one side of one of the non-conductive plies 48.

There has thus been described a novel type of electrically heated blanket having an improved heater unit designed for maximum durability and efficiency and yet having safety features not found in previous articles of this class. It will be readily apparent to one skilled in the art that certain changes may be made without departing from the spirit of the invention. For example, the heater unit could be used within other fabric structures such as aviators' suits; the rubber gridwork could take forms other than that illustrated, such as diagonal strips or cellular honeycomb structures and the mode of attachment to the fabric might be by other means, as by thermosetting rubber cements. Various types of temperature sensitive elements could also be used in conjunction therewith.

We claim as our invention:

1. A self-supporting heating element comprising a plurality of ribbons of electrically conducting rubber, means for connecting said ribbons in parallel to a source of current, a plurality of temperature sensitive resistors in heat transfer relation to said ribbons, and means connecting said resistors in circuit, said connecting means comprising a metallic conductor embedded within a ribbon of non-conducting rubber integrally secured to said electrically conducting rubber ribbons.

2. A self-supporting heating element comprising a gridwork of relatively narrow, thin flexible ribbons of electrically conducting rubber, said gridwork comprising a plurality of longitudinally extending ribbons and a plurality of transversely extending ribbons, all of said ribbons being integrally united at their crossover points, and means

for connecting said ribbons in parallel to a source of electrical current.

3. A heater element for an electrically heated blanket, or the like, comprising a grid of thin transverse and longitudinal self-supporting rubber strips integrally secured at their crossover points, transverse strips of said grid having outer plies of non-conducting rubber and an inner ply of electrically conducting rubber, some of the longitudinal strips of said grid having outer plies of non-conducting rubber and an inner ply of electrically conducting rubber having embedded therein flexible metallic electric conductor, and others of said longitudinal strips being of non-conducting rubber having a flexible metallic electrical conductor embedded therein, a plurality of temperature-sensitive resistors positioned adjacent said other longitudinal strips and connected in circuit with said last mentioned electric conductor, means including said some longitudinal strips connecting said transverse strips to a source of current, and means connecting said temperature-sensitive resistors to a control circuit for regulating the supply of current to said heater element.

4. A heater unit comprising a self-supporting heating element and an envelope of loosely woven, non-conducting, filamentous material for said heating element, said heating element comprising a gridwork of relatively narrow, thin, flexible ribbons of electrically conducting rubber, said grid-

work comprising a plurality of longitudinally extending ribbons and a plurality of transversely extending ribbons, all of said ribbons being integrally united at their crossover points, and means for connecting said ribbons in parallel to a source of electrical current.
